UNITED STATES PATENT OFFICE.

AUGUSTE GREMAUD AND EDOUARD VILAIN, OF MARSEILLE, FRANCE.

STUFF-COMPRESSING MACHINE.

Application filed December 22, 1920. Serial No. 432,448.

To all whom it may concern:

Be it known that we, AUGUSTE GREMAUD and EDOUARD VILAIN, the first a citizen of the Helvetic Confederation, and the second 5 a citizen of the Republic of France, residing at Marseille, in the Republic of France, have invented new and useful Improvements in Stuff-Compressing Machines, of which the following is a specification.

- 10 This invention relates to improvements in compressing machines, and more particularly to machines of the class used in manufacturing pharmaceutical, chemical and edible products by compressing a pulverized, 15 granular or pasty material into the form of tablets, the object of the invention being to provide an improved machine of this character which is simple in construction, and very efficient and reliable in operation.
- 20 With the foregoing and other objects in view, which will appear as the description proceeds, the invention consists in the novel features of construction and combination of parts which will be more fully described 25 hereinafter and particularly pointed out in the claims.

In the drawings accompanying and forming part of this specification,

Fig. 1 is a vertical, longitudinal section 30 of a machine constructed in accordance with the present invention; and

Fig. 2 is a horizontal section thereof.

The same characters of reference designate the same parts in the different figures 35 of the drawings.

Referring to the drawings, 1 is a casing in which the rotatable elements are carried. A shaft 2 is mounted for rotation in the side walls of the casing, said shaft having 40 secured at one end thereof outside of the casing a fly wheel 18 and at the opposite end a driving pulley 19. Within the casing, the shaft 2 carries an eccentric cam 4 and a pair of eccentrics 3, one at each side of 45 the cam, said cam being in the form of a cylinder truncated in the direction of its length, as shown in Fig. 1. The casing 1 is provided with an extension 1^a, projecting laterally from said casing, said extension 50 being provided with a pair of transverse walls 1^b and 1^c thereby to form within the extension a pair of recesses or cylinders, one at each end thereof, for the reception of a pair of sliding members or pistons 7 and 8, 55 each of which carries a plunger, 9 and 10

respectively, said plungers being in alignment and extending toward each other and guided in the transverse walls 1^b and 1^c of the casing extension 1^a. The piston 7 is provided with an anti-friction roller 6 in contact with the cam 4, while the piston 8 is connected with the eccentrics 3 by means of a pair of connecting rods 5, each having at one end a sleeve portion 5^a encircling its respective eccentric. The cam 4 and eccentrics 3 are so disposed and formed that they reach their maximum eccentricity at the same time. Between the transverse walls 1^b and 1^c, the casing extension 1^a is provided with a third wall 1^d, in which is supported a matrix 11 having a central opening in axial alignment with the plungers 9 and 10 for receiving the ends of said plungers. The wall 1^d is spaced sufficiently far from the walls 1^b and 1^c to form at one side of the wall 1^d a feeding chamber or port 14 and at the other side a delivery chamber or port 15, the lower end of the chamber 14 being closed by a removable bottom plate 16 forming a trap, whereby all of the material remaining in the chamber after the operation of the machine ceases, may be removed.

In order to ensure the constant contact of the roller 6 with the cam 4 and at the same time maintain the ends of the pistons 9 and 10 the proper distance apart at all times, the piston 8 is formed with an interior chamber within which is carried a slidable member 12, which is actuated by a coiled spring 13 supported on an inwardly extending boss 90 formed on the end wall of said chamber. A pair of push rods 17 are slidably carried by the casing 1^a, each having one end engaging the piston 7 and its opposite end passing through the end wall of the piston 8 95 and engaging the slidable member 12.

The operation of the machine is as follows:

Power may be applied to the pulley 19 from any suitable source of power for driving the shaft 2. For each revolution of the shaft 2, the plungers 9 and 10 are reciprocated one complete stroke by means of the cam 4 and eccentrics 3 and their connections. Assuming the position of the parts at the 100 beginning of the operation to be as shown in the drawings, and the direction of rotation of the shaft to be toward the left, it will be seen that with the diameter $c-a$ in horizontal position the plunger 9 occupies about 110

one-half of the length of the matrix 11, while the plunger 10 is just entering said matrix. If the shaft be now rotated through an angular distance of 90° , the diameter 5 $b-b$ will be horizontal and the roller 6 will be in contact with the flat portion of the cam 4, so that the plunger 9 will be in its extreme retracted position, while plunger 10 will be at its extreme extended position. In 10 passing to this position, however, while the plunger 10 has continuously progressed, the plunger 9, owing to the shape of the cam 4, has been held more or less stationary, so that while the ends of both plungers are 15 within the matrix the space 20 between said ends is decreased thereby compressing any material that is confined in said space, and upon the sudden passage of the roller 6 from the curved to the flat surface of the cam 4, 20 the space 20 becomes wider and reaches its maximum width when the point d of the shaft is nearest the roller 6, at which time the end of the plunger 9 has been retracted so as to be approximately flush with the 25 surface of the wall 1^b, while the plunger 10 has been extended so as to be flush with the rear end of the matrix, thereby pushing the compressed tablet into the chamber 15. Upon the next angular movement of the shaft 2 30 through a distance of 90° , that is, a distance sufficient to carry the diameter $a-c$ into horizontal position, with the point c nearest the roller 6, the opposite operation from that just described takes place, namely, the 35 plunger 10 is continuously retracted within the matrix while the plunger 9 is suddenly extended toward the plunger 10, thereby again reducing the width of the space 20 until the two plungers are again in the position 40 shown in the drawings. Upon the next angular movement of 90° , which carries the diameter $d-b$ into horizontal position, with the point b nearest the roller 6, the plunger 10 is completely withdrawn from the 45 matrix 11 and retracted until it is approximately flush with the surface of the wall 1^c, and the plunger 9 is extended slightly into the chamber 14, at which time the distance between the ends of the plungers is again increased to its maximum. Upon the next 50 angular movement of 90° , which brings the diameter $c-a$ into horizontal position, with the point a nearest the roller 6, the plungers are brought to the position shown in the 55 drawings, the plunger 9 having during its retracting movement created a partial vacuum in the matrix and thereby sucked in material from the chamber 20, which material is compressed between the two plungers during the next angular movement of 90° , as 60 hereinbefore described. It will be understood, of course, that during the operation of the machine, the feeding chamber 14 is kept constantly filled with the material to be 65 compressed. During the extending move-

ments of the plunger 9, the spring 13 is compressed by means of the slide rods 17, so that when said plunger has reached its limit of extension, the spring acts to cause retraction thereof with the roller 6 in contact with the 70 surface of the cam 4.

From the foregoing, it will be seen that if the chamber 14 is kept supplied with material during operation of the machine, such material will be automatically carried into 75 the matrix between the plungers 9 and 10 and thereby compressed into tablets, which tablets are discharged into the chamber 15, when they may be removed either by gravity or by any suitable mechanism provided for 80 that purpose.

Having thus described our invention, what we claim is:

1. A compressing machine, comprising, in combination, a casing, a matrix secured within said casing, said casing having a feeding chamber at one side of the matrix and a delivery chamber at the opposite side thereof, a pair of aligned plungers carried by said casing and extending toward each other, and means for reciprocating said plungers through said chambers and matrix both in the same direction but at different speeds and with their opposed ends spaced apart, the distance between said ends being 90 at its maximum within the chambers and at its minimum within the matrix.

2. A compressing machine, comprising, in combination, a casing, a matrix secured within said casing, said casing having a feeding chamber at one side of the matrix and a delivery chamber at the opposite side thereof, a pair of aligned plungers carried by said casing and extending toward each other, said plungers being adapted to be moved together in the same direction, a piston carried by each of said plungers and reciproitable within said casing, a rotatable shaft, a pair of eccentrics carried by said shaft and connected with one of said pistons for reciprocating the same, a cam carried by the shaft for moving the other piston in one direction, and means carried by the first piston for maintaining the second piston in contact with its cam thereby to move it in the opposite direction.

3. A compressing machine, comprising, in combination, a casing, a matrix secured within said casing, said casing having a feeding chamber at one side of the matrix and a delivery chamber at the opposite side thereof, a pair of aligned plungers carried by said casing and extending toward each other, said plungers being adapted to be moved together in both directions, a piston carried by each of said plungers and reciproitable within said casing, a rotatable shaft, means carried by said shaft for reciprocating one of said pistons, means carried by the shaft for moving the other piston in one di- 120 125 130

rection, and flexible means for moving said last piston in the opposite direction.

4. A compressing machine, comprising, in combination, a casing, a matrix secured with 5 in said casing, said casing having a feeding chamber at one side of the matrix and a delivery chamber at the opposite side thereof, a pair of aligned plungers carried by said casing and extending toward each other, said 10 plungers being adapted to be moved together in both directions, a piston carried by each of said plungers and reciprocable within said casing, a rotatable shaft, means carried by said shaft for reciprocating one of

said pistons, means carried by the shaft for 15 moving the other piston in one direction, a spring carried by said first piston, and means between said second piston and said spring for placing the same under tension when the piston is moved by said first means.

In testimony whereof we have signed our names to this specification.

AUGUSTE GREMAUD.
EDOUARD VILAIN.
